UNITED STATES PATENT OFFICE.

SIGFRID MILLER, OF OAKLAND, CALIFORNIA.

AUTO-BED.

1,276,095.

Specification of Letters Patent. Patented Aug. 20, 1918.

Application filed March 14, 1918. Serial No. 222,469.

To all whom it may concern:

Be it known that I, SIGFRID MILLER, a citizen of the United States, residing at Oakland, in the county of Alameda and 5 State of California, have invented new and useful Improvements in Auto-Beds, of which the following is a specification.

This invention relates to an auto bed, and particularly to improvements over the structure shown in my co-pending application entitled "Folding bed," filed September 24th, 10 1917, Serial Number 192,887.

One of the objects of the present invention is to provide a simple, substantial, 15 cheaply manufactured folding bed for automobiles, which is adapted to be secured to the running board in such a manner that it may be readily extended outwardly when used or folded up on the running board in a 20 compact unit when traveling.

Another object of the invention is to provide a mattress frame of novel construction, which is foldable and which is provided with legs and braces for its support, when 25 extended, and also with a tent support which permits the bed to be inclosed or covered when desired.

Further objects will hereinafter appear.

The invention consists of the parts and 30 the construction and combination of parts as hereinafter more fully described and claimed, having reference to the accompanying drawings, in which—

Figure 1 is a perspective view, showing 35 the bed extended.

Fig. 2 is a side elevation, showing the bed in folded position.

Fig. 3 is a perspective view of the locking bar for securing the bed on the running 40 board when in the folded position.

Referring to the drawings in detail, A indicates the running board of an automobile and 2 a pair of brackets secured thereto. Pivotally mounted, as at 3, in said brackets 45 is a bed-frame, generally indicated at B, in which is mounted a wire mattress 4 of suitable construction. The bed-frame is in the present instance constructed of three sections 5, 6 and 7; these sections being respectively 50 termed the intermediate section, the inner section, and the outer section. The inner

section is pivotally attached, as at 3, to the brackets 2 at one end and at the opposite end it is pivotally attached to the intermediate section, as at 8. The outer section is 55 pivotally attached, as at 9, to the opposite end of the intermediate section, thus forming a bed-frame which may be folded up to assume a rectangular-shaped, compact bundle, such as shown in Fig. 2. 60

The bed is also provided with a pair of supporting legs 10 and 11, one set being pivotally secured by the pins 8 which connect the intermediate frame with the inner frame, while the opposite set of legs are pivotally attached, as at 12, to the outer frame section. Each set of legs is provided with toggle braces 13 and the legs 11 are each provided with a tie rod 14, the outer end of which is hook-shaped to engage a pin 15 on 70 the outer legs 10. The manner of pivotally mounting the legs and connecting the toggle braces 13 and the tie rods 14 permits the legs, braces and rods to be folded up parallel with the bed-frame sections; the legs 10 with 75 attached rods 14 and toggle braces 13 being folded parallel with the inner section 6, while the legs 11, with the connected toggle braces, fold up and lie parallel along the sides of the outer frame section. This structure also rigidly braces the bed when extended, something which is of great value when it is considered that the ground upon which the bed is supported is very often 80 uneven. 85

The intermediate section 5 is braced crosswise by a bar 16, thus preventing the frame sections from being drawn together and the pivotal connections from binding. The bed is otherwise provided with a foot-frame 17. 90 The lower end of this foot-frame is bent at right angles, as shown at 18, and is pivotally secured at this point, as at 19, to the outer frame section. The foot-frame is also provided with a pair of spring latches 20 engageable with the underside of the outer frame, as shown in Fig. 1. These latches rigidly secure the foot-frame in the vertical position and it is, therefore, possible to utilize the foot-frame as a support for the 95 outer end of a tent or canopy, such as indicated at 21. This canopy may be attached in 100

any suitable manner, for instance, by buttons or hooks, to the top of the automobile and may also be provided with fastenings secured to the sides or bottom of the frame sections, thus permitting the bed to be entirely inclosed or covered when desired.

The foot-frame not only serves the function of a support for the canopy but it also serves as a bedding clamp, when folded down; that is, the right angular bends formed on the lower ends adjacent to the pivotal connections are just sufficiently long to form a space between the foot-frame and the mattress which permits the foot-frame to hold the bedding in position while the bed-frame as a whole is being folded up or extended. The bed may be constructed of angle iron or any other suitable material and as comparatively little strength is required it can readily be seen that the amount of material employed will not be sufficient to weigh down the side of the automobile on which it is mounted.

The bed, as previously stated, is supported by two pairs of legs 10 and 11 which are positioned near the outer end, while the inner end is supported by the brackets 2. A three-point support is in this manner provided which serves as a solid foundation capable of supporting the bed rigidly on practically any ground.

The brace 16 is provided with a sliding bracket, such as shown in Fig. 3. This bracket consists of two sections 25 and 26. The section 25 embraces the lateral brace or pipe and can, therefore, slide longitudinally thereon while the section 26 is hook-shaped, as shown, to engage and straddle the side of the automobile, thus securing the bed-frame, when folded, in a vertical position. The sections 25 and 26 may be slotted, if desired, and secured together with one or more screws to permit it to be lengthened or shortened to suit different sizes of automobiles. The inner sides of the hook 26 may be lined with felt, such as shown at 27, or any other suitable material to prevent the body or the upholstery from being scratched or marred.

The materials and finish of the several parts, may of course, be such as the experience and judgment of the manufacturer may dictate, and I wish it understood that various changes in form, proportions and minor details of construction may be resorted to within the scope of the appended claims.

Having thus described my invention, what I claim and desire to secure by Letters Patent is—

1. A folding bed for automobiles, comprising a mattress-carrying frame, a pivotal connection between the frame and the running board, a bar extending crosswise of the frame, a locking member carried by said bar

adapted to secure the frame against movement when folded up on the running board, 65 said locking member comprising a bar turnably and slidably mounted on the rod, and a hook-shaped member formed on the outer end of said bar adapted to straddle the side of the automobile.

2. A folding bed for automobiles, including a frame composed of foldable sections, means to pivotally connect the inner section to the automobile running board, a transverse bar connected to one of the sections to 75 brace the latter and to underlie same when the frame is extended and to overlie said last named section when the frame is folded, a bracket slidably borne by said bar, and means on the bracket extending beyond said 80 last named section in folded vertical position of the frame to engage over the top edge and on opposite side faces of a side of the automobile body to hold the frame folded and against movement.

3. A folding bed for automobiles, including a frame composed of foldable sections, means to pivotally connect the inner section to the automobile running board, a bar connected to one of the sections so as 90 to underlie same when the frame is extended and to overlie same when the frame is folded and means borne by the bar and extending beyond said last named section in folded vertical position of the frame to 95 engage over the top edge and on opposite side faces of a side of the automobile body to hold the frame folded and against movement.

4. In a folding bed for automobiles, 100 brackets formed for securement to the automobile running board, a foldable bed frame having an inner section pivoted to the brackets, an outer section, means to pivotally connect said sections, said means when the bed frame is folded being disposed at the top of the folded frame and said outer section when the frame is folded having its lower end engaged with and held against rearward movement by the brackets, said means being of substantially the length as that of the brackets so that when the sections are folded the latter will lie approximately parallel, and means borne by the first named means to engage the automobile body 110 to hold the frame folded.

5. A folding bed for automobiles, including a frame composed of an inner section, means to pivotally connect the inner section to the automobile running board, an intermediate section pivoted to the inner section, an outer section pivoted to the intermediate section, said sections when folded being arranged with the inner and outer sections vertically disposed and the intermediate section horizontally disposed and at 120 125

the tops of the inner and outer sections, and means carried by the intermediate section to secure the sections to the automobile in folded position of the sections, said means 5 when the bed frame is extended underlying the latter and when the bed frame is folded overlying the intermediate section.

In testimony whereof I have hereunto set my hand in the presence of two subscribing witnesses.

SIGFRID MILLER.
